UNITED STATES PATENT OFFICE.

STEPHEN KRONBURGER, OF HOBOKEN, NEW JERSEY, ASSIGNOR TO RAYMOND A. BURTON, FREDERICK J. MEERLENDER, AND WAL-TER T. JENNINGS.

DESIGN FOR A HEAD FOR BELT-PINS OR SIMILAR ARTICLES.

SPECIFICATION forming part of Design No. 36,945, dated June 7, 1904.

Application filed February 5, 1904. Serial No. 192,242. Term of patent 3½ years.

To all whom it may concern:

Be it known that I, STEPHEN KRONBURGER, a citizen of the United States, residing at Hoboken, in the county of Hudson and State of New Jersey, have invented a new, ornamental, and original Design for a Head for Belt-Pins or Similar Articles, as shown in the accompanying drawing.

The single figure of the drawing shows a head for belt-pins and similar articles ornamented according to my new design and illustrates the invention.

What I claim as new is—

The ornamental design for a head for belt-pins and similar articles herein shown.

STEPHEN KRONBURGER.
